EGG VENDING MACHINE

Heinz Braunsberg, Bristol, Conn.

Application July 5, 1957, Serial No. 46,851

Term of patent 14 years

(Cl. D52—3)

The figure is a front perspective view of an egg vending machine, showing my new design.

The undisclosed side and the rear of the vending machine are substantially plain in appearance.

I claim:

The ornamental design for an egg vending machine substantially as shown, and described.
